HYDRAULICALLY OPERATED MACHINE

Robert R. Raber, West Hartford, Conn., assignor
to Pratt & Whitney Company, Hartford, Conn.,
a corporation of New Jersey

Application April 18, 1931, Serial No. 531,240

4 Claims. (Cl. 121—47)

This invention relates to hydraulic operating means for machine tools and in particular to means for operating the hydraulic system to limit the stroke of the hydraulically moved element; and also to provide means for rendering the hydraulic mechanism again operative after effecting stopping of the hydraulically operated element.

An object of importance of the invention is to positively actuate one of the distributing valves of the hydraulic system to stop reciprocation of the hydraulically moved element in a predetermined limiting position.

Another object of the invention is to effect release of the distributing valve while the hydraulically operated member engaged by a table dog is retained in the position to which it is moved thereby, thus permitting normal operation of the table to be resumed.

And finally it is an object of the invention to provide safety means to limit the table movement by a part of the hydraulic mechanism so that the table can not be moved beyond safe limits at opposite ends of its movement.

With these and other objects in view, my invention consists in the features of construction and operation set forth in the following specification and illustrated in the accompanying drawings.

In the accompanying drawings annexed hereunto and forming a part of this specification, I have shown my invention embodied in a reciprocating table surface grinder but it will be understood that the invention can be otherwise embodied and that the drawings are not to be construed as defining or limiting the scope of the invention, the claims appended to this specification being relied upon for that purpose.

In the drawings:
Figure 1 is a front elevation of a grinding machine to which the present invention is shown applied.

Fig. 2 is a sectional view of one of the valves of the hydraulic system showing its relation to a plunger forming a part of this invention.

Fig. 3 is a front elevation of the valve operating member showing one of the actuating dogs on the hydraulically reciprocated table and its connections to a valve of the hydraulic system.

Fig. 4 is a side elevation of the mechanism shown in Fig. 3, showing also the table reversing rocker.

Fig. 5 is a detail view of the normal means for controlling the operation of the valve shown in Fig. 2.

Fig. 6 is a fragmentary view in front elevation

of a set of table reversing dogs and the controller lever operated thereby.

Fig. 7 is a vertical sectional view taken on the plane of line 7—7, and

Fig. 8 is a similar view taken on the plane of line 8—8.

In the above mentioned drawings I have shown but one embodiment of the invention which is now deemed preferable, but it is to be understood that changes and modifications may be made within the scope of the appended claims without departing from the spirit of the invention.

In the operation of hydraulic actuated machine tools it is desirable to provide a positive safety device rendering the hydraulic system inoperative as soon as the table or other part operated hydraulically reaches a critical or limiting position to prevent overrunning this safe limit. For this purpose the table or member operated hydraulically is provided with dogs or cams so positioned

that they may act upon and render the hydraulic system inoperative when the element reaches a critical position in each direction of travel. Engaging these cams is a mechanically operated device acting upon a valve in the hydraulic system to positively move the valve to a neutral or inoperative position. The invention also comprehends a releasable connection in the device

acting upon the valve so that the valve may be returned to its operative position while the table remains in its limited position and the mechanically operated device remains in its actuated position. The invention also comprehends setting the table reversing means in position to reverse the table simultaneously with operation of the safety stopping means at one end of the table travel. By this means the safety stop may be employed to rapidly bring the table to a stop in an extreme position for loading and unloading the table or other purpose, after which operation

may be resumed without delay.

Referring more in detail to the figures of the drawings, I show an application of the present invention to a grinder having a reciprocating table. Basically the machine includes a base 10 having a column on which is slidably movable a head 11. Rotatably mounted in this head is an abrasive wheel 12 of any preferred form. Slidable on the base 10 below the wheel 12 is a table

13 on which may be secured work pieces such as shown at W to be ground. This table, adjacent its ends, is provided with dogs indicated generally at 14, the position of which is determined by the maximum stroke for which the table may be

designed. These dogs 14 are supplementary to

65

the adjustable dogs 48, presently to be more fully described, adjustably positioned for any given or desired stroke. The dogs 14 are designed to prevent any movement of the table beyond safe limits in either direction. These dogs 14 therefore may be fixed permanently in position upon the table 13 in positions to engage the upper end of a vertically movable bar or rod 19, presently to be more fully described when the table 10 reaches the end of its travel.

The dogs 14 are provided with inclined cam surfaces 15 engaged by a rearwardly extending lug 19^a (Fig. 4) upon the upper end of the vertically movable bar 19. The cam surfaces 15 are such that the rod 19, as the table 13 moves in either direction so that a surface 15 engages the lug 19^a, is first forced to move to an extreme upward position. Thereafter any continued movement of the table 13 in the same direction forces the lug 19^a and its rod 19 downward. An oppositely inclined surface 16 on the cam is provided to effect this downward movement of the rod 19 and lug 19^a. A downwardly inclined surface 18 on a cam member 17 positively forces the rod 19 downward by engagement with a roller 19^b on the rod 19. When thus moved downward the rod 19 is maintained in its downward position by engagement of its roller 19^b with the horizontal surface 18^a of the cam member 17. 30 This surface 18^a extends parallelly to the direction of movement of the table and maintains the roller 19^b and rod 19 against any upward movement.

The vertically movable rod 19 is supported adjacent its upper end by being slidably mounted within a suitable bracket 20 attached rigidly in position upon a portion of the base 10. This rod 19 is provided with a pivotally mounted handle 22 spring pressed in a direction as shown in Fig. 40 to maintain the handle 22 in position to hold down a plunger 21 presently to be described. Upon being oscillated upon its pivot 23 to the position shown in dot-and-dash lines in Fig. 4 40 the handle 22 allows the plunger 21 to move vertically upward. Preferably and as indicated in Figs. 3 and 4 the lower end of the bar or rod 19 has a recess extending axially from its lower end so that the plunger 21 extends freely within the recess within the rod 19. The upper end of the plunger 21, with the handle member 22 in the position shown in full lines, engages a notched portion thereof so that so long as the handle member 22 remains in this position the plunger 21 must move down with downward movement of the rod. As soon, however, as the handle 22 is moved to the position shown in dot-and-dash lines, the plunger 21 may move upward within the rod or bar 19 as by means of a spring presently to be referred to. The handle member 22 is pivoted to the bar 19 at its upper end, as indicated at 23, and its vertically disposed portion may enter an elongated slot formed in the bar 19. The handle 22 will therefore retain its engagement with the upper end of plunger 21, and 55 will be normally retained in engaging position by its spring.

This plunger 21 is slidably mounted in a fixed housing member 25 adjacent the hydraulic control mechanism and is provided along one side 70 with a number of rack teeth. These rack teeth are adapted to engage a pinion 27 upon a horizontally disposed shaft 26 rotatably mounted upon a fixed axis within the fixed member 25. The fixed member 25 may be attached by any convenient means (not shown) to a portion of the

base 10, the upper end of the plunger 21 extending from the fixed member 25 and entering the opening within the rod 19 as above described.

On the shaft 26 carrying the pinion 27 engaging the rack teeth on plunger 21 is a larger gear 28 also fixedly mounted on the shaft 26 so that vertical movement of the plunger 21 will effect rotative movement of this gear 28 with the pinion 27. This latter gear 28 is in mesh with rack teeth on a horizontally disposed plunger 30 slidably mounted for axial movement within the fixed support 25. One of the ends of this horizontally movable plunger 30 extends outside the fixed member 25 and abuts against the end face of a control valve 31 of the hydraulic system. Movement of plunger 30 to the left will therefore move valve 31. Movement of the horizontal plunger 30 in the one direction is limited by a suitable plug 31^a closing one end of the opening for the plunger 30 in the retaining member 25.

The valve 31, as shown in Figs. 2 and 3, is provided with a spring 39 pressing against one end, so mounted that its effect is to normally force the plunger 30 in a direction away from the valve 31. Preferably and as shown, the spring 39 may be housed within a recess provided in the plunger 30, one end bearing against a pin 40 extending through the plunger 30. The opposite end of the spring 39 takes up against a suitable abutment 40^a within the housing 25, the plunger having an elongated slot to permit free movement thereof.

In the position of the valve 31 shown in Fig. 2, ports are open to admit fluid under pressure from the pressure supply conduit 33, past the reduced or necked portion 32 of the valve 31 into a conduit 34 leading to a reversing or distributing valve controlling the admission of fluid to opposite ends of a cylinder to actuate the table 13. This is the position of the valve 31 assumed during normal operation of the grinding machine, the fluid after entering the conduit 34 being distributed by any suitable form of hydraulic mechanism (not shown). Conduits 36 are provided on opposite sides of the above described ports to discharge any fluid leaking past portions of the valve 31. As soon as the roller 19^b upon the upper end of the rod 19 engages one of the cam surfaces 18 and is moved downward, the horizontal plunger 30 is moved to the left and forces the valve 31 to a position considerably to the left of the position shown in full lines. With the valve 31 in this left-hand position, the pressure supply conduit 33 is open directly to a return conduit 35 by the necked portion 32 of the valve 31 so that the fluid instead of going to the cylinder for effecting reciprocatory movements of the table 13 is bypassed to suitable exhaust passage without any effect upon the table movement.

The rod 19 above referred to is normally held in operative relation to the plunger 30 as shown in full lines in Fig. 2 so that the vertical plunger 21 when the rod 19 is engaged by one of the cam surfaces 18 will move the plunger 30 to its extreme left position and move the valve 31 toward the left as above described. Movements of the upper end of the rod 19 by engagement of the lug 19^a with the cam surfaces 15 and 16 takes place only when the table 13 approaches its extreme limits of travel. After the table 13 has been brought to rest after depressing of the rod 19, means must be provided to release the valve 31 so that normal operation may be resumed. For this purpose the handle 22 may be manually moved to its dot-and-dash position. With the handle 22 withdrawn to the dot-and-dash or in-

operative position shown in Fig. 4, with the rod 19 in its lower position the plunger 21 is released from its engagement with the rod 19 at the notched portion of the handle and therefore releasing the horizontal plunger 30 so that the valve 31 is free to be moved to its position shown in Fig. 2 by spring 39. Should the table 13 approach its limit position while the handle 22 is in the position shown in dot-and-dash lines in which the vertical plunger 21 is disengaged from the handle 22 and the rod 19, the following takes place. The lug 19^a first engages the inclined surface 15 so that continued movement of the table 13 first raises the rod 19 to its uppermost position. In this elevated position the rod 19 is in position to engage the handle member 22 over the upper end of the plunger 21, thus rendering the plunger 21 operable by the rod 19. Further movement of the table 13 causes the roller 19^b to engage the oppositely inclined surface 18 on the cam or dog 14 so that the rod 19 and plunger 21 are moved downward in the manner above described.

In Fig. 5 the operating connections for normally controlling the valve 31 are shown. The left-hand end of the valve 31 has a circumferential recess 38 engaging an arm of a bell crank lever 41 pivotally mounted at 42 within the base 10. The other arm of bell crank lever 41 is pivoted to a reach arm 44. To retain the bell crank lever 41 in any of its oscillated positions and therefore retain the valve 31 in any of its operative positions a detent 43 is provided. Preferably and as shown, the detent 43 is spring pressed toward the arm of lever 41 and its forward end enters one of the angular notches.

At the upper end of the reach arm 44 is connected a handle 45 pivoted at 46 in the base. By oscillatory movement of handle 45 movements of the valve 31 may be obtained to start and stop operation of the machine.

In Figs. 1 and 6 are shown the table reversing dogs adjustable along the length of the table 13 to vary its operative stroke. These dogs 48 will be suitably spaced apart for varying strokes of the table and will be positioned in opposed relation to each other. These dogs are shown generally at 48 and are slidably mounted upon suitable ways formed upon the table 13. By means of catch levers 49 on the dogs 48 engaging teeth of a rack 50 secured to the table 13 the position of the dogs 48 may be easily adjusted. Fixed to a shaft 51 disposed horizontally in the base so that they may oscillate said shaft are table reversing or controller arms 52 and 53 adapted to contact respectively with the dogs 48. Preferably each of these arms 52 and 53 is provided with a roller 54 for engaging one or the other of the cam surfaces of dogs 48. Also on shaft 51 is a controller lever 55 adapted for manual oscillation. Operation of this lever 55 either by hand or by the cam surfaces on dogs 48 acting on the arms 52 and 53 effects reversal of movement of the table by action of one of the hydraulic distributing valves. As the operation of the hydraulic mechanism by oscillation of this lever 55 forms no part of this invention and may be of usual or standard construction, the mechanism will not require description and is not shown. In the position shown in Fig. 6 the table is traveling in the direction of the arrow and is on the point of being reversed by engagement with the roller 54 on arm 52 by surface 56 of dog 48.

Associated with the dog 14 adjacent one end of the table 13 operating the rod 19 is a dog 57 secured in fixed position upon the table 13 as shown

most clearly in Fig. 6. On this dog 57 is surface 58 engaged by the roller 54 upon arm 52. By means of this dog 57 the hydraulic mechanism is reversed by oscillation of the table reversing lever 55 simultaneously with engagement of the rod 19 with the cam surfaces of the dog 14 adjacent cam 57. The hydraulic mechanism by operation of lever 55 is therefore set for reverse travel of the table 13 when the rod 19 acts upon the valve 31. As soon therefore as the starting lever 45 is operated to again start the table, the table starts upon its return stroke.

By reference to Fig. 4 it will be seen that the cam surfaces of the two opposed dogs 48 are in adjacent planes and the rollers 54 engaging them are out of alignment with each other and disposed for operative engagement respectively with said surfaces. The dog 57 has its roller engaging surface in alignment with the outermost dog 48. By this arrangement the reversing lever 55 carrying the arms 52 and 53 is free to be oscillated by this cam surface.

The reversing lever 55 and the arms 52 and 53 are movable axially a slight distance on the shaft 51, as indicated in dotted lines in Fig. 4. This is provided for the purpose of moving the rollers 54 out of engagement with the surfaces of dogs 48 so that the rollers 54 can pass their respective surfaces on the dogs 48 when the table is to be brought to its extreme end position.

What I claim is:

1. A stop mechanism for a hydraulically actuated member including in combination, a cam carried by said actuated member, a rod mounted upon the base on which said member is actuated and one end of which intercepts the path of movement of said cam, said rod being moved in opposite directions by engagement with said cam, means to effect engagement of said rod with said cam in any position of said rod, a valve in the hydraulic system for controlling the supply of fluid for operating said member, a plunger for moving said valve in one direction when said rod is moved downward, and means to disengage said rod from operative connection with said plunger permitting return movement of said valve while said rod is retained by said cam in its downward position.

2. A stop mechanism in combination with a hydraulically actuated member including in combination, a cam carried by said actuated member, a rod mounted upon the base on which the member is actuated and one end of which intercepts the path of movement of said cam, said rod being moved in opposite directions by engagement with said cam, means to effect engagement of said rod with said cam in any position of said rod, a valve in the hydraulic system for controlling the supply of fluid for operating said member, said valve being moved in one direction by downward movement of said rod, and being so held by said rod, said valve being movable in either direction while said rod is in its upper position, and means to render the rod inoperative to hold said valve while said rod is held down by said cam whereby return movement of said valve is permitted.

3. A stop mechanism in combination with a hydraulically actuated member including in combination, a cam carried by said member, a rod mounted upon the base on which said member is actuated and said rod movable in opposite directions by engagement with said cam upon movement of the hydraulically actuated member to a predetermined position, a valve in the hydraulic system for controlling the supply of fluid for ac-

tuating said member, said valve being actuated by movement of said rod in one direction, said rod holding the valve in its actuated position to stop movement of the hydraulically actuated member, said valve being movable in either direction while said rod is at the end of its return movement in the opposite direction, means to cause said rod to actuate said valve as the member approaches the end of its movement, and 10 means to release said valve from its rod actuated position while said hydraulically actuated member is in said predetermined position.

4. A stop mechanism for a hydraulically actuated member including in combination, spaced
